(57) **CLAIM**

The ornamental design for an input panel of electronic lock, as shown and described.

DESCRIPTION

FIG. 1 is a top, front and right side perspective view of an input panel of electronic lock showing our new design; FIG. 2 is a bottom, rear, and left side perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front elevation view thereof; and,

FIG. 8 is a rear elevation view thereof.

The broken lines in the drawings illustrate portions of the input panel of electronic lock which form no part of the claimed design.

1 Claim, 8 Drawing Sheets
